APPARATUS FOR MAKING MUFFLERS

Clarence M. Buck, Jackson, Mich., assignor to
 Hayes Industries, Inc., Jackson, Mich., a corporation of Michigan

Application April 29, 1940, Serial No. 332,174

15 Claims. (Cl. 153—80)

The present invention relates to apparatus for attaching baffles to muffler tubes and more particularly to apparatus which positively aligns the baffles in a predetermined relation.

Before the employment of outwardly projecting louvers on muffler tubes, it was the practice to provide baffles having central openings through which the muffler tube was disposed and then to spot weld the baffles onto the tubes to secure them in position. However, since the employment of louvers having projecting portions came into use, it was necessary to make the opening in the baffles of such a size as to clear the louvers. Since the openings in the baffles were of such size as to prevent a snug fit on the portion of the tube not provided with louvers, it was then necessary to crimp the baffles in order to bring the central opening down to a size whereby the baffles could be secured to the tube by some convenient method such as spot welding. The crimping operation is unsatisfactory as such and is expensive. Particularly unsatisfactory is the misalignment of the baffles that results in making difficult subsequent telescoping over the baffles of an outer shell or tube. Another practice has been to roll ridges in sheet metal before rolling it into muffler tubes and then mounting baffles on the ridges on the tubes. An example of this practice is disclosed in Patent No. 1,878,424 to Oldberg. This method is unsatisfactory because in lock seaming the muffler tubes, the ridges are crushed.

According to the present invention, apparatus is provided for expanding limited lengths of the muffler tube into peripheral contact with enlarged openings in the baffles. As an additional refinement, a bead is struck up from the expanded portions of the tube on each side of the baffles to prevent axial movement of the baffles with respect to the tube. When baffles are assembled on muffler tubes by using apparatus according to the present invention, an alignment of the baffles is obtained which makes the telescoping of an outer shell or tube onto the baffles a simple matter and a muffler section is obtained wherein there is a degree of peripheral engagement between the baffles and the inner and outer tubes not possible when employing prior assembling practices.

The invention, however, may be used also to secure baffles to muffler tubes where the opening in the baffles approximates the external diameter of the tubes. The method of assembling muffler parts and the muffler produced thereby are disclosed and claimed in my co-pending application executed on an even date herewith.

An object of the present invention is to pro-

vide apparatus for radially expanding a limited portion of a through muffler tube onto a baffle disposed on the outside thereof.

A further object of the invention is to provide apparatus for radially expanding a portion of the through muffler tube onto a baffle disposed on the outside thereof and to form a bead on either side of the baffle to prevent axial movement of the baffle with respect to the tube.

10 A still further object of the invention is to provide apparatus for securing baffles to through muffler tubes which comprises an internal and external support for the through tube and internal, radially expanding dies associated with the internal support, together with mechanism for radially expanding the internal dies to expand a portion of the through tube into engagement with a baffle on the outside of the tube.

A still further object of the invention is to provide apparatus for expanding a seamed muffler tube onto baffles without opening the seam.

These and other objects will be apparent from the following specification when taken with the accompanying drawings in which:

25 Fig. 1 is a partial vertical section of a part of the structure comprising the present invention.

Fig. 2 is a partial plan view of a part of the structure comprising the present invention.

30 Fig. 3 is an end view of one of the clamping units and the actuating mechanism therefor.

Fig. 4 is an enlarged detail of a portion of Fig. 1, showing the expanding action of the expanding dies.

35 Fig. 5 is a view similar to Fig. 4 showing an enlarged section of another portion of Fig. 1.

Fig. 6 is a vertical section through the mandrel, quill and expanding dies on line VI—VI in Fig. 5.

Fig. 7 is a side view of one of the expanding dies.

Fig. 8 is a side view of another one of the expanding dies.

Fig. 9 is a section on the line IX—IX of Fig. 4.

Fig. 10 is a section on the line X—X of Fig. 3.

Fig. 11 is a section on the line XI—XI of Fig. 1.

Fig. 12 is a plan view of a part of the structure of the present invention completing the plan view shown in part in Fig. 2, and

Fig. 13 is a side view of a part of the structure 50 of the present invention completing the view shown in part in Fig. 1.

The drawings disclose apparatus according to the present invention for securing two groups of baffles to a muffler tube, the baffles in each group having different diameters although the differ-

ence in baffle diameters is not an essential of the invention. Briefly, the invention consists of supporting the baffles in clamping units in a predetermined relation, disposing the muffler tube through the openings in the baffles while they are supported in the clamping units, and then projecting a quill and mandrel assembly carrying expanding dies into the tube. The dies are moved radially outwardly to expand limited portions of the muffler tube into engagement with the baffles to clamp the baffles on the muffler tube. The dies are actuated by a hydraulic cylinder which moves the mandrel relatively to the quill and the quill and mandrel are moved into and out of the muffler tube by means of a pneumatic cylinder.

Referring particularly to the drawings, the reference character 1 indicates a table, disclosed particularly in Figs. 1, 2 and 3, supporting clamping units 2, 3 and 4. The clamping units 2 and 3 are arranged for receiving baffles 5 of one size and the clamping unit 4 is designed for receiving baffles 6 of another size of smaller diameter than the baffles 5. Each clamping unit 2, 3 and 4 is provided with an upper and a lower half. Fig. 3 illustrates an end view of the clamping unit 3 and serves to illustrate the general form and operation of each of the clamping units 2, 3 and 4. As shown, the clamping unit 3 is provided with a swingable upper half 7 and a stationary lower half 8, the two halves being connected by a pivot 9. The lower half 8 is mounted on a base 10 and is provided with a rearwardly extending ear 11. The upper half 7 is provided with an upwardly projecting ear 12, shown in Figs. 2 and 3. Connecting the ears 11 and 12 is a toggle consisting of upper link members 13 and lower link members 14 placed on opposite sides of the ears 12 and 11 respectively. The inner ends of the links 13 and 14 are pivoted to each other on opposite sides of a block 15.

The base 10 extends rearwardly from the table 1 and is provided on opposite sides thereof with upwardly extending ears 20. Between the ears 20 there is pivoted at one end a pneumatic cylinder 21, provided with compressed air inlet and exhaust conduits 22. A piston 23, within the cylinder 21, is provided with a piston rod 24 which is connected to the block 15. By moving the piston 23 to the right, as viewed in Fig. 3, the piston rod 24 and the block 15 will move to the right to bend the toggle, consisting of the links 13 and 14, in the center to pivot the upper half 7 of the clamping unit 3 about the pivot 9. A spring pressed stop 26 is provided to absorb the shock and limit the opening of the top half 7 of the clamping unit 3.

As shown particularly in Fig. 2, the clamping unit 2 is actuated by a cylinder 27 and the clamping unit 4 is actuated by a cylinder 28. It will be understood that the piston 29 in the cylinder 27 acts through its piston rod 30 to actuate a toggle mechanism 35 to lift the top half of the clamping unit 2 and that the piston 36, in the cylinder 28, acts through its piston rod 37 to actuate a toggle mechanism 38 to lift the top half of the clamping unit 4.

The clamping units 2 and 3 are provided with chambers 39 for receiving and clamping the baffles 5 and the clamping unit 4 is provided with chambers 40 for receiving and clamping the baffles 6. When the cylinders 27, 21 and 28 have been actuated to lift the top halves of the clamping units, 2, 3 and 4 respectively, baffles 5 and 6 are placed in the lower halves of the chambers

39 and 40 respectively. While the upper halves of the clamping units 2, 3 and 4 are raised, the muffler tube 41, which is to receive the baffles 5 and 6, is disposed manually through the openings in the baffles 5 and 6 and is positioned against an adjustable stop 42, shown particularly in Figs. 1 and 2. The stop 42 is secured to the table 1 by a screw 43, passing through an elongated slot 44 in the base plate 45 of the stop 42. By raising the screw 43 and moving the base plate 45 longitudinally of the table 1, the position of the stop 42 may be varied to correctly position the muffler tube 41 with respect to the clamping units 2, 3 and 4. Adjacent the stop 42 is a rest 46 suitably secured to the table 1, on which the outer end of the muffler tube 41 is supported. The top surface of the rest 46 is provided with a curved tube receiving slot 47. When the muffler tube 41 has been inserted in the baffles 5 and 6, the cylinders 27, 21 and 28 are actuated to close the clamping units 2, 3 and 4 to clamp the baffles 5 and 6 and the muffler tube 41 therein as herein-after explained.

For the purpose of adjustment, the clamping units 2, 3 and 4 are slidable longitudinally on the table 1 and maintained in alignment by a key 48, shown in Fig. 3, the key way therefor being partly in the table 1 and partly in the bases of the clamping unit. In view of the fact that apparatus, according to the present invention may be employed for a variety of combinations of clamping units and thus baffles, the table 1 is provided with holes for receiving securing screws by which the clamping units may be secured thereto. As shown particularly in Fig. 3, the clamping unit 3 is secured to the table 1 by securing screws 49, projecting through the base 10 into the table 1. It will be understood also that in the use of the machine, additional clamping units may be employed, or the clamping units employed may be for use with baffles of only one size, rather than two sizes, as shown.

When the muffler tube 41 and baffles 5 and 6 have been arranged in position within the clamping units 2, 3 and 4, the structure for expanding spaced portions of the muffler tube 41 into contact with the baffles 5 and 6 is inserted. This structure consists of a quill 55 having concentrically disposed therein a mandrel 56. The quill 55 is of very slightly less external diameter than the internal diameter of the tube 41, and the mandrel 56 is slidably disposed within a longitudinal bore 57, within the quill 55.

The quill 55 and the mandrel 56 and their associated parts are disclosed broadly in Fig. 1, and more specifically in Figs. 4 through 9. Reference to Figs. 1 and 6 discloses the expanding dies which consist of a plurality of segments 58, carried by the quill 55, there being one set of expanding die segments 58 for each baffle to be secured to the tube 41. The expanding dies are disclosed more particularly in Figs. 6, 7 and 8. Fig. 6 discloses a section through the mandrel 56, the quill 55, and one set of die segments 58. Each complete expanding die consists of four segments 58, disposed in slots 59 in the quill 55. Figs. 4 and 5 disclose enlarged cross-sectional portions of the mandrel 56 and the quill 55, together with portions of the baffles 5 and 6, and the expanding die segments 58, associated therewith. Each die segment is provided with a follower member 60, projecting through slots in the quill 55 to the bore 57 therein. The follower members 60 extend into operative association with inclined cam grooves 61 in the mandrel 56.

Associated with each die segment 58 is a cantilever leaf spring 62, having one end thereof anchored in a slot 63, in the quill 55. Each spring 62 has the free end thereof radially movable in a slot 64 in the quill 55 and is stressed to normally urge associated die segments 58 radially inwardly by bearing on shoulders 65 thereon. The springs 62 continuously urge the die segments 58 into engagement with the inclined surfaces of the cam grooves 61 respectively. By reference to Figs. 1, 4 and 5, it will be observed that when the mandrel 56 is moved to the left, as shown, with respect to the quill 55, the die segments 58 will be cammed radially outwardly against the opposition of the springs 62, and further than when the mandrel 56 is moved to the right, with respect to the quill 55, the springs 62 will urge the die segments 58 radially inwardly.

The die segments 58 are shown particularly in Figs. 6, 7 and 8. One of the die segments 58 of each set, as shown particularly in Fig. 6, is provided with a groove 66, disposed in alignment with an axially extending groove 67 in the surface of the quill 55. The grooves 66 and 67 are for the purpose of receiving the lock seam 68 in the muffler tube 41. Since the groove 66 is provided in one of the die segments 58 of each set, the lock seam 68 will not act to distort the muffler tube 41 upon expansion of the die segments 58 and cause a discontinuous engagement between the tube 41 and the baffle being secured. It is preferred that the depth of the grooves 66 in the die segments 58 be such that they snugly receive the lock seam 68 and will therefore expand that part of the muffler tube 41, including the lock seam 68, into contact with the baffles being secured.

Of the four die segments 58, comprising each set, two of them are provided at opposite ends thereof with tongues 70 for cooperative disposition in grooves 71 in adjacent die segments 58. The tongues 70 and grooves 71 interlock, as shown in Fig. 6, so that as the die segments 58 are cammed radially by the inclined surfaces of the camming grooves 61, to expand axially spaced parts of the muffler tube 41 into engagement with the baffles 5 and 6, there will not be a continuous axial line of separation between the die segments 58, with the result that a continuous line of engagement between the muffler tube 41 and the baffles 5 and 6 is obtained.

It will be observed that each of the die segments 58 is provided with a pair of spaced ridges 72. The ridges 72 of each die segment 58 when taken together, form for each expanding die a pair of rings which project radially outwardly to provide ridges or beads 73 in the muffler tube 41, which project radially outwardly on either side of the flange 74 with which each baffle is provided. The beads 73 serve to positively prevent any axial movement of the baffles after the tube 41 has been expanded into contacting engagement therewith by the die segments 58. While the ridges 72 disclosed in the drawings are continuous on each die segment 58 and provide substantially continuous beads 73 in the muffler tube 41, it is contemplated that in place of ridges 72 there may be provided a plurality of spaced projections which would result instead of substantially continuous beads in the muffler tube 41, a plurality of circumferentially aligned small protuberances which would function identically the same as the beads 73.

In operation of the apparatus, according to the present invention, after the baffles 5 and 6

have been placed in the lower halves of the clamping members 2, 3 and 4, the muffler tube 41 has been inserted through the baffles 5 and 6, and the upper halves of the clamping units 2, 3 and 4 have been closed upon the lower halves thereof, the baffles 5 and 6 and the muffler tube 41 are clamped in a predetermined fixed relation. This fixed relation is such that the baffles 5 are in axial alignment as a group and the baffles 6 are in axial alignment as a group. Then when the quill 55 and the mandrel 56 are inserted in the muffler tube 41 and the die segments 58 are expanded into engagement with the flanges 74 of the baffles 5 and 6, the alignment of the outer peripheries 58, expanding portions of the muffler tube 41 into contact with the baffle flanges 74. The result is that the groups of baffles being in alignment may readily telescopically receive outer tubes.

As will be apparent from Fig. 1, the clamping members 2 and 3 take one form, and the clamping member 4 takes another form, although the functions of the two forms are the same. The clamping members 2 and 3 each comprise a body portion 75, which as shown in Fig. 3, comprises two halves 7 and 8, pivoted at 9. Each half of the body portion 75 is provided with a backing member 76, and a housing member 77, separated by a spacing member 78. The housing members 77 and spacing members 78 are connected to the body members 75 by bolts 79. As will appear particularly in Figs. 1 and 4, the chambers 39 for receiving the baffles 5 are annular in configuration and are defined by the backing members 76, the housing members 77 and the spacing members 78. The spacing members 78 are particularly designed to be replaced by spacing members of such size as may be required to provide chambers 39 of the correct size for a given baffle size.

As shown more clearly in Fig. 4, the backing members 76, together, provide a backing up ring 80 for backing up the flange 74 of each baffle 5 during the expanding of the muffler tube 41 under the action of the die segments 58. Each backing up ring 80 should be of such a width that it will fit between the beads 73 provided by the ridges 72 in the die segments 58. Furthermore, the diameter of each ring 80 should be slightly greater than the desired final diameter of the flanges 74 of the baffles 5 so that as the die segments 58 are withdrawn, after expanding the muffler tube 41, the inherent resiliency of the flanges 74 and the expanded sections or ridges 81 of the muffler tube 41 will contract the expanded sections 81 and the flanges 74 to their desired diameter, and will not contract the expanded sections 81 away from the flanges 74.

The backing up members 76 also provide supplementary rings 82, the halves of which bear against the muffler tube 41 when the clamping units 2 and 3 are closed, to support and align the muffler tube 41 in a predetermined position, prior to and during the expanding action of the segments 58. In the form of the invention shown, the supplementary rings 82 have a somewhat less internal diameter than the backing up rings 80. This is because the form of the apparatus shown is for use in securing baffles to muffler tubes when the baffles have sufficiently large openings to permit them to be moved over the externally projecting louvers 83 with which the muffler tube 41 is provided. However, it is considered, as disclosed in my co-pending application executed on

even date herewith and filed herewith, that the invention is equally applicable for securing baffles to muffler tubes which are not provided with externally projecting louvers. In such a case, the baffles may have openings approximating the size 5 of the muffler tube to which they are to be secured, and therefore it would not be necessary to expand the sections 81 of the muffler tube 41 so greatly as shown. Consequently the difference between the internal diameter of each backing up ring 80 and the internal diameter of its associated supplementary ring 82 need not be nearly so great as illustrated in Fig. 4. It will be understood, as is well known in the art, that baffles are secured to portions of the muffler tubes 15 in which there are no louvers.

As shown particularly in Fig. 1, the body members 15 are connected for convenience on oppositely disposed sides of the chamber 39 forming members 16, 18 and 17. This arrangement is provided for preventing interference between the supporting and operating mechanism for the clamping units 2 and 3. However, it will be appreciated that if it were desired to space the baffles 5 further apart, that there would be no interference and that the said opposite arrangement of the parts, as disclosed in Fig. 1, need not be resorted to.

The clamping unit 4, differing in form but not function from the clamping units 2 and 3, is provided with a pair of body members 90, comprising upper and lower halves 91 and 92 respectively, which are pivoted together in the same manner as the upper and lower halves 7 and 8 of the clamping unit 3, as shown in Fig. 3. To the body member halves 91 and 92 are secured opposed supporting sections 93 and 94, as shown in Fig. 1. To the supporting sections 93 are secured by screws 97, backing members 95 and housing members 96. Likewise, to the supporting sections 94 are secured, but to opposite sides thereof, backing up members 98 and housing members 99, by screws 100. It will be seen from the drawings that the backing members 95, together with the housing members 96 and the backing members 98, together with the housing members 99, provide the annular chambers 40 for receiving baffles 6. The parts of the clamping unit 4 function in the same manner as the corresponding parts of the clamping units 2 and 3.

Each backing up ring 80 of the clamping units 2, 3 and 4 is provided with an ejecting pin 101 disclosed particularly in Figs. 3 and 10. The pins 101 are disposed in bores 102 and are provided with pistons 103 which are disposed in enlarged bores 104. Springs 105 in the bores 104 resiliently bear against the pistons 103 to urge the pins 101 upwardly to eject each muffler and baffle assembly after baffles have been secured on a muffler tube 41 and the clamping units 2, 3 and 4 opened.

For moving the quill 55 into and out of the muffler tube 41 there is provided beneath the table 1 a pneumatic cylinder 110, having suitable air inlet and outlet conduits 111. The cylinder 110 is provided with a piston rod 112, to which is connected a piston rod 113 as shown in Fig. 1. The piston rod 113 is in turn connected to a bracket 114, depending from a carriage 115, supported from the table 1 on sliding plates 116, as shown in Figs. 1 and 11. The connection between the piston rod 113 and the bracket 114 is provided by a cap 117, threaded to the end of the piston rod 113, and by an annular dog 118 clamped by screws 119 to the bracket 114.

Supported on the carriage 115 is a hydraulic cylinder 120 having a piston 121 to which is connected a piston rod 122, in turn connected by a coupling 123 to the mandrel 56, as shown in Figs. 1 and 2.

The coupling 123 consists of a block 124, having the piston rod 122 threaded thereto. The block 124 is provided at one end thereof with a semi-circular recess 125, having therein a ridge 126 and a removable semi-circular cap 127 having a recess corresponding in configuration to the semi-circular recess 125. The mandrel 56 is provided with a groove 128 for receiving the ridge 126 and the corresponding portion of removable cap 127. The cap 127 is secured to the block 124 by screws 129 to provide a positive yet separable connection between the mandrel 56 and the block 124.

The quill 55 is connected to a member 135, connected by screws 136 to the carriage 115. The connection between the quill 55 and the member 135 is similar to the connection between the mandrel 56 and the block 124, the connection being separable by virtue of a removable cap 131, secured to the member 135 by screws 138 shown particularly in Fig. 2.

The connection between the bracket 114 and the carriage 115 consists of a restricted extension 139 (see Fig. 11) projecting upwardly through a slot 140 in the table 1, and a guiding plate 141 disposed between the inside faces of the sliding plates 116. The bracket 114 together with the guiding plate 141 are connected to the carriage 115 by bolts 142. The slot 140 in the table 1 extends longitudinally of the table 1, as disclosed in Fig. 12, to permit longitudinal movement of the carriage 115 under the action of the pneumatic cylinder 110. As shown, Figs. 1 and 13, which taken together, provide a complete side view of the apparatus, according to the present invention, with parts thereof in section, the bracket 114 with its extension 139 is located adjacent the right end of the carriage 115. In Fig. 13, there is disclosed a guide for the left end of the carriage 115. This guide consists of a guiding plate 145 similar to the guiding plate 141, disposed between the sliding plates 116, a block 146 disposed in the slot 140 and a plate 147 disposed beneath the table 1 and overlapping the edges of the slot 140. The parts 145, 146 and 147 are secured by screws 148 to the carriage 115.

In order to reinforce the action of the screws 136 in supporting the member 135 from the carriage 115, there are disposed between the hydraulic cylinder 120 assembly and the member 135, a pair of tubes 149. Bolts 150 are disposed through openings in the member 135 and through the tubes 149 into threaded engagement with the hydraulic cylinder 120 assembly to clamp the tubes 149 between the member 135 and the hydraulic cylinder 120 assembly.

The hydraulic cylinder 120 is provided with inlet and outlet conduits 151 for conducting hydraulic fluid for controlling the movement of the piston 121. The operation of the apparatus is as follows: When the hydraulic cylinder 120 is at the left end of the table 1, or in other words, at the opposite end of the table 1 to which it is shown in Fig. 12, the quill 55 together with the mandrel 56 are spaced laterally from the clamping units 2, 3 and 4. By manipulating a suitable control valve (not shown), compressed air is directed to cause the pistons in the cylinders 21, 21 and 28 to open the clamping units to permit the insertion of baffles 5 and 6 in the lower halves

of the chambers 39 and 40. The muffler tube 41 is then disposed through the openings in the baffles 5 and 6 and aforesaid suitable control valve is manipulated to actuate the pistons in the pneumatic cylinders 27, 21 and 28 to close the clamping units 2, 3 and 4 to clamp the baffles 5 and 6 in a predetermined aligned position and to rigidly support the muffler tube 41 with respect thereto. Then a suitable control valve (not shown) is manipulated to cause the piston 112 in the cylinder 110 to move from the left end thereof, as viewed in Fig. 1, to the right to move the carriage 115 together with the hydraulic cylinder 120, and also, the quill 55 and the mandrel 56 to the right to insert the quill 55, together with the mandrel 56 into the muffler tube 41. Following this movement, a suitable valve (not shown) is manipulated, preferably automatically, to move the hydraulic piston 121 to the left as viewed in Fig. 13, to move the mandrel 56 to the left, as shown in Figs. 1, 2, 4 and 5, to cause the inclined surfaces in the cam grooves 61 to cam the die segments 58 outwardly to expand spaced restricted portions of the muffler tube 41 into engagement with the flanges 74 of the baffles 5 and 6 as hereinabove explained.

Since the hydraulic cylinder 120, which actuates the mandrel 56, and the member 135, which supports the quill 55, are both supported from the carriage 115, it will be clear that the thrust resisting the movement of the piston 121 in the hydraulic cylinder 120 is absorbed by the carriage 115, so that during the relative movement between the quill 55 and the mandrel 56, there is no stress on the pneumatic cylinder 110 and its associated parts or between the carriage 115 and the table 1. Upon the completion of the expanding, of the muffler tube 41 by means of the die segments 58, the piston 121 of the hydraulic cylinder 120 is moved to the right, as viewed in Figs. 1 and 13 to permit the cantilever leaf springs 62 to move the die segments 58 radially inwardly from engagement with the expanded portions 81 of the muffler tube 41. The quill 55 and the mandrel 56 may be then withdrawn from the muffler tube 41 and this result is accomplished by moving the piston 112 in the pneumatic cylinder 110 to the left to move the carriage 115 and the structure mounted on it to the left. The clamping units 2, 3 and 4 may then be opened, the muffler tube 41 with the baffles 5 and 6 secured thereto removed, and new baffles 5 and 6 inserted in portions of the chambers 39 and 40 respectively, of the lower halves of the clamping units 2, 3 and 4 to start a new cycle of operation.

It is to be understood that within the scope of the present invention other combinations of clamping units than the units 2, 3 and 4 disclosed may be employed, and different forms of clamping units if desired may be employed. Furthermore, it is contemplated as disclosed particularly in my aforesaid co-pending application, that at the same time, baffles may be secured to a muffler tube, which have relatively large openings and relatively small openings, with respect to the tube to which they are being secured, it being understood that those baffles with relatively large openings are for disposition over outwardly projecting louvers and that those baffles with relatively small openings are for use where there are no outwardly projecting louvers, or where there are no louvers at all in the portions of the tube over which the baffles must be moved to bring them into the desired relation for affixation to the tube.

While the baffles disclosed in the drawings and described above are annular in configuration with concentrically disposed openings, it is to be understood that the invention is equally applicable to securing baffles which are of some other configuration than annular, as for instance, elliptical, and which have openings therein which are not concentric, but which are disposed to one side of the center.

- 10 Having thus described my invention, what I desire to secure by Letters Patent and claim is:
1. A device of the character described for securing a plurality of baffles having annular flanges outlining openings therein to a tube projecting through said openings, comprising a mandrel for receiving a tube thereon, a plurality of radially expanding dies, each comprising a plurality of circumferentially aligned expanding dies on said mandrel, means to fixedly support said baffles in a predetermined axial alignment and radially opposite said radially expanding dies respectively, means for projecting said dies outwardly to radially expand the tube onto said flanges, and means to engage the outside of the tube to support the same while the expanding dies are moved radially outwardly to expand the tube onto the flanges.
  2. A device of the character described for securing baffles having annular flanges outlining openings therein to a tube projecting through said openings, comprising a mandrel for receiving a tube thereon, a plurality of sets of circumferentially aligned expanding dies on said mandrel, means to fixedly support said baffles in a predetermined axial alignment, means for projecting said sets of dies outwardly respectively to radially expand the tube onto said flanges, and relatively fixed means to engage the outer periphery of said flanges to support the same while the expanding dies are moved radially outwardly to expand the tube onto the flanges, whereby when said baffles are secured to said tube they are in said predetermined axial alignment.
  3. The invention as defined in claim 1 wherein the expanding dies are provided with marginal beads for forming circumferential ridges in the tube at the edges of the flange for locking the same against axial movement relative to the tube.
  4. A device of the character described for securing a baffle having an opening therein to a tube projecting through said opening, comprising a rod for receiving a tube thereon, a plurality of circumferentially aligned expanding dies supported by said rod, and means for projecting said dies radially outwardly to radially expand the tube into engagement with said baffle for securing the same to said baffle, said dies having adjacent edges in overlapping relation circumferentially of said tube, whereby said dies in all positions of radial movement provide together a continuous circumference.
  5. A device of the character described for securing a baffle having an opening therein to a tube projecting through said opening, comprising a mandrel having a quill telescoped thereon for receiving and supporting a tube thereon, a plurality of circumferentially aligned expanding dies supported by said quill, and camming means supported by said mandrel for projecting said dies outwardly to radially expand the tube into engagement with said flange, said quill having openings therein through which the camming connection between said camming means and dies is effected.
  6. A device of the character described for se-

curing a baffle having an annular flange outlining an opening therein to a tube projecting through said opening, comprising a mandrel having a quill telescoped thereon for receiving a tube thereon, a plurality of circumferentially aligned expanding dies supported by said quill, and having portions circumferentially overlapping portions of said quill, said quill having openings therein through which portions of said dies project to said mandrel, said openings having walls preventing movement of said dies longitudinally of said quill, said mandrel having camming means engaging with said dies for projecting said dies outwardly to radially expand the tube into engagement with said flange, and means to move said mandrel with respect to said quill to actuate said camming means.

7. A device of the character described for securing a baffle having an opening therein to a tube projecting through said opening comprising a mandrel having a quill telescoped thereon for receiving and supporting a tube thereon, a plurality of circumferentially aligned expanding dies supported by said quill, camming means supported by said mandrel for projecting said dies outwardly to radially expand the tube into engagement with said baffle, and spring means supported by said quill for urging said dies into engagement with said camming means, said quill having openings therein through which the camming connection between said camming means and dies is effected.

8. A device of the character described for securing baffles having central openings therein to a tube projecting through said openings, comprising a cradle, means to clamp a plurality of baffles in said cradle in a predetermined alignment, a mandrel having a quill telescoped thereon for disposition in a tube disposed through the baffle openings, a plurality of sets of circumferentially aligned expanding dies supported by said quill, there being one set for each baffle, and camming means supported by said mandrel for projecting said dies outwardly to radially expand portions of the tube beneath said baffles respectively into engagement with said baffles.

9. A device of the character described for securing a baffle having an opening therein to a tube projecting through said opening, comprising means to support a baffle and a tube projecting therethrough in predetermined fixed relative positions, a mandrel having a quill telescoped thereon for disposition in said tube, said quill supporting said tube, means for feeding said mandrel and quill into said tube, a plurality of circumferentially aligned expanding dies supported by said quill, camming means carried by said mandrel for projecting said dies outwardly to radially expand the tube into engagement with said baffle, and means to actuate said mandrel to actuate said camming means to project said dies outwardly, said quill having openings therein through which the camming connection between said camming means and dies is effected.

10. A device of the character described for securing a baffle having an opening therein to a tube projecting through said opening, comprising means to support a baffle and a tube projecting therethrough in a predetermined fixed relation, a mandrel having a quill telescoped thereon for disposition in said tube, said quill supporting said tube, means for feeding said mandrel and quill into said tube, a plurality of circumferentially aligned expanding dies supported by said quill, camming means carried by said mandrel

for projecting said dies outwardly to radially expand the tube into engagement with said baffle, and means to move said mandrel axially with respect to said quill, to actuate said camming means to project said dies outwardly, said quill having openings therein through which the camming connection between said camming means and dies is effected.

11. A device of the character described for securing a baffle having an opening therein to a tube projecting through said opening, comprising means to support a baffle and a tube projecting therethrough in a predetermined fixed relation, a mandrel having a quill telescoped thereon for disposition in said tube, said quill supporting said tube, means for feeding said mandrel and quill into said tube, a plurality of circumferentially aligned slots having bottoms in said mandrel, the bottoms of said slots being inclined to the longitudinal axis of said mandrel and comprising camming surfaces, a plurality of circumferentially aligned expanding dies having portions projecting into said slots and into engagement with said camming surfaces, said quill having openings through which portions of said dies extend into said slots, and means to move said mandrel longitudinally with respect to said quill to cause said camming surfaces to act against the portions of said dies in contact therewith to project said dies outwardly to radially expand the tube into engagement with said baffle.

12. A device of the character described for securing a baffle having an opening therein to a tube projecting through said opening, comprising means to support a baffle in fixed position, a mandrel having a quill telescoped thereon for disposition in a tube disposed through said opening in said baffle, means for feeding said mandrel and quill into said tube, a plurality of circumferentially aligned expanding dies supported by said quill, said dies having portions circumferentially overlapping portions of said quill, camming means carried by said mandrel for projecting said dies outwardly to radially expand the tube into engagement with said baffle, and means to move said mandrel axially with respect to said quill to actuate said camming means to project said dies outwardly.

13. A device of the character described for securing a baffle having an opening therein to a tube projecting through said opening, comprising means to support a baffle having an opening therein in fixed position, a mandrel having a quill telescoped thereon for disposition in a tube disposed through said opening in said baffle, a carrier, a connection between said quill and carrier, actuating means mounted on said carrier, said actuating means being connected to said mandrel, means to move said carrier for moving as a unit said carrier, quill and mandrel to project said quill and mandrel into said tube, a plurality of circumferentially aligned expanding dies supported by said quill, means carried by said mandrel for projecting said dies outwardly to radially expand the tube into engagement with said baffle, and means to actuate said actuating means on said carrier to move said mandrel axially with respect to said quill to actuate said projecting means to project said dies outwardly.

14. A device of the character described for securing a baffle having an opening therein to a tube projecting through said opening, comprising means to support a baffle having an opening therein in fixed position, a mandrel having a quill telescoped thereon for disposition in a tube dis-

posed through said opening in said baffle, a table, a carrier on said table, a connection between said quill and said carrier, actuating means mounted on said carrier, said actuating means being connected to said mandrel, a slot in said table, a bracket connected to said carrier and projecting through said slot, means disposed on the opposite side of said table from said carrier connected to said bracket to move said carrier along said table for moving as a unit said carrier, quill and mandrel and for projecting said quill and mandrel into said tube, a plurality of circumferentially aligned expanding dies supported by said quill, means carried by said mandrel for projecting said dies outwardly to radially expand the tube into engagement with said baffle, and means to actuate said actuating means on said carrier to move said mandrel axially with respect to said quill to actuate said projecting means to project dies outwardly.

15. A device of the character described for securing a baffle having an opening therein to a

5 tube projecting through said opening, comprising means to support a baffle in fixed position, a mandrel having a quill telescoped thereon for disposition in a tube disposed through said opening in said baffle, a table, a carrier on said table, a connection between said quill and said carrier, moving means mounted on said carrier, said moving means being connected to said mandrel, means to move said carrier along said table for moving as a unit said moving means, said quill and mandrel and for projecting said quill and mandrel into said tube, radially movable means on said quill for expanding a limited portion of said tube into contact with said baffle for securing the same to said baffle, means on said mandrel for actuating said radially movable means, and means to actuate said moving means on said carrier to move said mandrel axially with respect to said quill to actuate said actuating means on said mandrel.

20 CLARENCE M. BUCK.
